UNITED STATES PATENT OFFICE.

JOHN SUPPER, OF PHILADELPHIA, PENNSYLVANIA, ASSIGNOR TO MARTIN STROH, OF SAME PLACE.

DESIGN FOR A HAND-WASHER.

SPECIFICATION forming part of Design No. 33,701, dated December 11, 1900.

Application filed November 8, 1900. Serial No. 35,869. Term of patent 3½ years.

To all whom it may concern:

Be it known that I, JOHN SUPPER, a citizen of the United States, residing in the city and county of Philadelphia, State of Pennsylvania, have invented and produced a new and original Design for Hand-Washers, of which the following is a specification, reference being had to the accompanying drawings, forming part thereof.

The leading feature of my design for a hand-washer is a head of oblong shape having a flat back, a serpentine working face of alternate ribs and depressions of corresponding curvatures, and serpentine sides of alternate ribs and depressions, the curves of the side ribs joining the curves of the working face, the several ribs and depressions extending in the direction of the long axis of the head and existing directly in said head.

Figure 1 represents a perspective view of a hand-washer embodying my design. Fig. 2

represents a transverse section thereof on line xx , Fig. 1.

In the drawings, A designates the hand-washer, the same consisting of the oblong head B, having a flat back, a serpentine face C, composed of the alternate ribs and depressions of uniform curvatures, and serpentine sides D, formed of alternate ribs and depressions. The curves of the side ribs join the curves of the working face, and the several ribs and depressions extend in the direction of the long axis of the head and exist directly therein.

Having thus described my invention, what I claim as new, and desire to secure by Letters Patent, is—

The design for a hand-washer substantially as shown and described.

JOHN SUPPER.
